(57) **CLAIM**

The ornamental design for a headgear, as shown and described.

DESCRIPTION

FIG. 1 is a top, front, and left side perspective view of a first embodiment of a headgear showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

Broken lines are used to illustrate portions of the headgear that form no part of the claimed design. The dash-dot broken lines depict the bounds of the claimed design and form no part thereof.
